CLAIM

The ornamental design for a modular clamp block for tubing, as shown and described.

DESCRIPTION

FIG. 1 is a perspective view of a modular clamp block for tubing showing my new design.

FIG. 2 is a top view thereof;

FIG. 3 is a bottom view thereof;

FIG. 4 is a rear view thereof;

FIG. 5 is a front view thereof;

FIG. 6 is a side view thereof; and,

FIG. 7 is an opposite side view thereof.

The features presented in broken lines illustrate portions of the modular clamp block for tubing that form no part of the claimed design.
